UNITED STATES PATENT OFFICE

2,604,207

APPARATUS FOR SEPARATING MAGNETIC MATERIAL

Walter J. Scott, Portland, Oreg.

Application February 1, 1949, Serial No. 73,894

1 Claim. (Cl. 209—218)

2

1 The present invention has to do with the magnetic separation of valuable components of materials found in many types and forms. For example, in many sections there are tremendous deposits of black sand, composed principally of silicates and magnetite with smaller percentages of such desirable elements as gold, scheelite, galena, titanium oxides, tin oxides and platinum. Other types of materials which may be treated in accordance with my process are of the rock ore type bearing small percentages of gold, silver, platinum or other valuable minerals, which ores may be finely crushed and treated in accordance with my process, provided that a portion of the ore comprises magnetic materials. Whether the material to be treated is found originally in the form of placer sands or solid bodies of ore which are crushed and ground as a preliminary to separation, an expensive, time-consuming step in the recovery of the valuable components heretofore has been the requirement that the mineral must be dried in order that separation may be accomplished. An object of my invention is to eliminate this costly step, making it possible to achieve separation with the material remaining in its original wet condition. By the use of my process magnetic sands may be sluiced or dredged from a riverbed or coastal shelf and passed through the separator in the condition in which they are drawn from the placer deposits. With the use of my process and apparatus the magnetic material may be entirely removed before the sand is passed through the usual riffles when the object is to obtain gold or the like from the sand. In passing gold-bearing black sand through a riffle device in accordance with the prior practices, I have noted that the riffles are rapidly clogged by the magnetite or similar heavy particles, since their specific gravity is such as to cause them to settle behind riffle bars. Gold particles in such sands are usually flattened or waferlike so that, even though their specific gravity may be three times as much as the specific gravity of the magnetite, they tend to skip and slide over the riffle bars as soon as the slightest concentration of magnetic sand causes the current to be deflected smoothly over the riffle bars without the usual back eddy or turbulence. Thus, even though the riffle does not appear to be dangerously filled, a great deal of the valuable elements are lost shortly after a riffle is placed in operation in a black sand area. With my invention the magnetite and other magnetic materials are entirely eliminated before the lighter, non-magnetic materials such as quartz sand are passed through the riffle device, with the result that a high efficiency is achieved.

5 In other types of mining operations the object of my invention is to recover magnetic materials which have value in themselves. It may not pay to recover magnetite as a source of iron or steel, but in many instances such sands contain minor percentages of ores of valuable elements such as tin or titanium which have the property of being attracted magnetically but to a lesser extent than magnetite. I am aware that many attempts have been made in the past to separate such material from the gangue by the use of magnetic separators, either wet or dry, and either singly or arranged in series of separators with different separating effects. However, it has been my observation that no such prior separating apparatus or process is successful, and I have concluded that it is due primarily to the tendency of the magnetic particles to build up clots of cohered particles which bind within themselves the non-magnetic or lesser magnetic particles, or form shelves or projections upon which the non-magnetic or lesser magnetic particles are supported, with the result that unwanted materials are trapped with the desired materials. With my invention I am able to cleanly separate relatively magnetic materials from relatively non-magnetic materials, either aggregating all 10 materials having some degree of magnetism, or separating only a certain material having a certain degree of magnetic properties. I am thus able entirely to separate the unwanted magnetic materials from gold, platinum or silver-bearing quartz sand which may later be passed through riffles, or first to separate magnetite from material bearing other ores of magnetic property which are desired and then to separate the other magnetic materials either from the residue which 15 remains after separating the magnetite or from the magnetite itself. The present invention is extremely rapid in operation and adds very little to the cost of equipment necessary to dredge or mine and crush the value-bearing materials.

20 25 30 35 40 45 50 The objects and advantages of the present invention may be more readily understood by inspection of the following specification taken in connection with the accompanying drawing wherein like numerals refer to like parts throughout, while the features of novelty will be more distinctly pointed out in the appended claim.

The drawing illustrates a schematic representation of a preferred embodiment of the mechanism by which the process is carried out. In 55 the drawing a relatively deep tank 10 is filled

with a liquid, preferably water, as indicated, and the sand or crushed ore is directed downwardly into the relatively quiescent water through an inlet 11, the sand or crushed ore preferably being carried along by a stream of water such as would be produced by the usual hydraulic dredge. The water level in the tank is maintained fairly constant by regulating an adjustable outlet 12 in the bottom of the tank.

At one side of the tank is located a pair of transverse drums 15, one located above the other, either one or both of which may be driven by suitable power means (not shown). The drums are preferably provided with teeth or cogs on their surfaces capable of engaging a series of magnets 16 strung together on a chain or chains 17 which are receivable in guiding grooves (not shown) in the surfaces of the drums. The chains are endless and pass about the drums 15 so that an endless magnetic belt is thus provided. The magnets may be permanent magnets or electromagnetic magnets supplied with current in any ordinary fashion. An endless belt 18 is trained about the drums 15 and offset drum 19 and guide roll 20 so as to provide a portion projecting laterally from above the top of the tank. Magnetic material which is attracted to the upwardly traveling reach of the belt 18 by the magnets 16 is held to the belt until the horizontal portion thereof is reached, whereupon the belt leaves the area of magnetic attraction but the material remains supported upon the horizontal section. As the belt travels about the drum 19 the magnetic material falls into a hopper or chute, the action being augmented by a doctor blade or section of the hopper wall 21 scraping the returning portion of the belt. The belt then travels downwardly through the tank and the cycle is repeated.

In accordance with the preferred embodiment of my invention, the distance between the drums 15 is considerable so that as the sands settle vertically through the water column alongside of the upwardly traveling belt the magnetic particles have sufficient opportunity to be attracted laterally toward the magnets. In the event that the purpose of the apparatus is to separate black sand from non-magnetic materials including gold flakes, perfect separation can be achieved particularly since the gold flakes flutter downwardly through the water, turning from side to side just as a dish settles into a body of water. In doing so they escape being trapped by the particles moving toward the belt and, likewise, the non-magnetic particles have opportunity to settle vertically downward without being trapped by the magnetic materials being built up on the surface of the belt. By controlling the magnetic force, such as by varying the number or strength of permanent magnets or by varying the current to electromagnets, the extent of attraction may be controlled so that only the magnetite will be attracted to the belt, thus permitting materials of lesser magnetic value to escape through the outlet 12. In a second operation, or in a separate separator located in series with the first one, the materials of lesser magnetic quality may then be separated from the non-magnetic materials such as quartz and clay; similarly, one material of lesser magnetic property than magnetite may be separated from a second material, or even lesser magnetic properties.

The degree of separation may also be affected by shifting the relative position of the inlet 11, the position thereof being dictated in accordance

with the particular qualities of the material being treated. If it is desired to separate all magnetic materials which can be separated, the inlet 11 may be placed close to the upper extremity of the belt so that by the time the particles have reached the lower extremity of the belt only non-magnetic particles remain in suspension in the water. If it is placed further away the apparatus may be caused to separate only a magnetic material of a certain degree of magnetic strength. Similar results may be obtained by altering the depth of the water. Similar effects, to a certain extent, may be achieved by controlling the speed of travel of the belt, but it is preferred that the other means of achieving control be utilized since increasing the speed beyond a certain point results in inefficient operation since the friction of the water washes material from the belt. A further degree of control may be achieved by providing an adjustable false wall 25, the position of which relative to the wall facing the upwardly traveling section of belt may be controlled by adjustment screws 26. The purpose of the false wall is to confine the material to a relatively small portion of the tank so that there will be no tendency for material to escape the magnetic field. However, in some cases it may be desirable to move the inlet 11 as far as possible away from the magnetic field, in which case the wall 25 might have to be similarly moved away from the magnets.

The present invention has the distinction over all prior apparatus within my knowledge in that the method embodied therein has the following characteristics: The material to be separated falls downwardly through a body of water in free suspension therein and the material which is magnetically attracted to the magnetic portion of the apparatus is removed vertically upward in a thin sheet without clots, fingers or shelves of material holding within or upon themselves undesired materials. The apparatus is preferably controlled in any of the foregoing manners so as to prevent more than the accumulation of a thin coating or sheet of magnetic material which is incapable of holding the non-magnetic particles. Further than that, the point of greatest accumulation is immediately adjacent the inlet to the tank so that only very strongly magnetic materials will be immediately attracted to the belt upon entering the water. The result is that at the lower extremity of the upwardly traveling section of the belt a very thin layer of material begins to accumulate, this layer increasing to its maximum extent adjacent the point of entry of the undivided material, but at no time being built up to an undesirable extent.

Having illustrated and described a preferred embodiment of my invention, it should be apparent to those skilled in the art that the invention permits of modification in arrangement and details. I claim as my invention all such modifications as come within the true spirit and scope of the appended claim.

I claim:

Apparatus for effecting the separation of fine, relatively magnetic and non-magnetic particles comprising a relatively deep tank, an inlet at the top of said tank through which a mixture of particles may be introduced in a liquid carrier, an outlet at the bottom of the tank capable of permitting the escape of liquid equal to the amount introduced with the material whereby to maintain a fairly constant depth of relatively quiescent

liquid in the tank, said inlet being arranged to direct the material into the top of the liquid in the tank whereby the particles may travel in freely falling suspension downwardly through the liquid in the tank, a traveling belt having a vertical portion thereof traveling upwardly through the liquid in the tank at one side of the path of free falling movement of the particles, a closely spaced series of magnets traveling with said belt in close proximity thereto at the side 10 of said vertical portion of the belt away from the falling particles for creating a magnetic field through which the particles fall whereby magnetic particles are attracted to and held onto the upwardly traveling portion of the belt, and means 15 for guiding a portion of said belt laterally from the upper region of said tank whereby particles removed from suspension by the traveling belt may be removed from the belt.
